[57] CLAIM

The ornamental design for a double ended spatula, as shown and described.

DESCRIPTION

FIG. 1 is a right side elevational view of a double ended spatula showing my new design;

FIG. 2 is a right side elevational view thereof in a jar shown in broken lines for illustrative purposes only;

FIG. 3 is a fragmentary front elevational view thereof;

FIG. 4 is a cross-section taken along line 4—4 of FIG. 6;

FIG. 5 is a top plan view thereof;

FIG. 6 is a fragmentary left side elevational view thereof;

FIG. 7 is a fragmentary rear elevational view thereof;

FIG. 8 is a bottom plan view of FIG. 6;

FIG. 9 is a top plan view of FIG. 11;

FIG. 10 is a fragmentary front elevational view thereof;

FIG. 11 is a fragmentary left side elevational view thereof;

FIG. 12 is a fragmentary rear elevational view thereof;

FIG. 13 is a bottom plan view thereof; and

FIG. 14 is a cross-section taken along line 14—14 of FIG. 11.
